UNITED STATES PATENT OFFICE

JOSEPH WILLIAM HELTZEL, OF WARREN, OHIO

MEANS FOR AND METHOD OF FINISHING CONCRETE SURFACES

Application filed March 24, 1925. Serial No. 17,940.

The present invention relates to means for and methods of finishing the surfaces of concrete roads, pavements, side-walks, floors, platforms, and the like, and aims to provide a novel and improved device for and method of pressing or rolling down high spots on the surface of the concrete, as well as smoothing the surface and having a straight-edge effect.

Another object of the invention is to provide an elongated roller of small diameter and of such weight as to exert the desired pressure on the concrete when the concrete has reached a certain stage of natural settling, so as to effectively finish the surface by pressing down the high spots, and driving out water and air that remain after the natural exuding of the greater portion thereof.

A further object is the provision of such a roller having separately or independently operable means at its opposite ends for moving the roller over the surface of the concrete, and permitting, if desired, either end to receive a moving force independently of the other end, for convenience and efficiency in using the roller.

A further object is the provision of a novel travelling bridge to move over the surface of the concrete and adapted to accommodate the finishing roller or device for movement across the surface of the concrete, and also having means for supporting the workmen.

A still further object is the provision of a travelling carriage or bridge in combination with a finishing roller or device and means carried by the carriage for moving said roller or device over the surface of the concrete; and another object, in this connection, is to provide means whereby the finishing roller or device may be carried by the carriage to be moved to different positions conveniently for successive finishing operations.

With the foregoing and other objects in view, which will be apparent as the description proceeds, the invention resides in the construction and arrangement of parts, as hereinafter described and claimed, it being understood that changes can be made within

the scope of what is claimed, without departing from the spirit of the invention.

The invention is illustrated in the accompanying drawings, wherein—

Figure 1 is a perspective view of the finishing roller or device as in use manually in connection with a travelling carriage or bridge. 55

Fig. 2 is a detail view showing one end portion of the roller in longitudinal section.

Fig. 3 is a plan view showing the roller 60 with modified operating means to be used interchangeably with the handles shown in Fig. 1.

Fig. 4 is a perspective view of one end portion of the roller as shown in Fig. 3. 65

Fig. 5 is a perspective view corresponding to Fig. 1 illustrating modifications wherein means are mounted on the carriage for moving the roller and for supporting the roller for movement with the carriage. 70

Fig. 6 is a cross section of the apparatus shown in Fig. 5.

In carrying out the invention the roller 7 is of comparatively long length, being from ten to sixteen feet long. A sixteen foot roller 75 is preferred, although a shorter roller may be desirable when working on steep hills. It is also essential that the roller be of small diameter and that it be sufficiently heavy to accomplish the purposes for which it is intended. The roller is about six inches in diameter, and has a weight of from 18 to 30 pounds per foot in length with a diameter of substantially six inches. If the roller is of smaller diameter then the weight thereof 80 per unit length is less, whereas if the roller is of larger diameter the weight per unit length is greater, so that the weight of the roller is in proportion to the area of contact of the roller with the concrete, such area of concrete increasing in proportion to the increase in diameter of the roller. The roller is cheaply and conveniently produced from a length of heavy pipe, such as a section of cast iron pipe, and may even be filled with 85 solid concrete or other weighting medium in order to obtain the desired weight of the roller. 95

As shown in Figs. 1 and 2, the operating means for pushing or pulling the opposite 100

- ends of the roller comprise bars 8 having outstanding handles 9 at their upper ends, and the lower ends of the handles are pivotally engaged with the opposite ends of the roller. 5 Thus, plugs 10 and other suitable members are secured in the ends of the roller and trunnions or pivots 11 may be screwed or otherwise secured within said plugs and engage through apertures in the bars 8 for 10 loosely connecting said bars with the roller. The bars 8 are disconnected and independent of one another, in order that two workmen may conveniently operate the roller on the surface of the concrete, as suggested 15 in Fig. 1. The illustration shows the device used for smoothing down the surface of a concrete road after the concrete has settled to a predetermined stage as hereinafter described. 20 A travelling carriage or bridge 12 is conveniently employed for operating the roller, having wheels 13 that roll on the side rails or forms 14 which define the edges or sides of the road. The carriage has boards or 25 planks 15 at its front and rear extending transversely across the road and spaced apart sufficiently to accommodate the roller between them. The workmen walk along the boards or platforms 15 in moving the roller 30 transversely across the road with the roller disposed substantially longitudinally of the road. The handle bars 8 may be used to push or pull the ends of the roller, or one man may pull the corresponding end of the roller while 35 the other man pushes his end of the roller. It is also possible for either workmen to push or pull his end of the roller while the other end of the roller is held against movement. This enables the roller to be angled 40 on the concrete surface, when desirable for smoothing down the concrete, or for advancing the roller in moving it forwardly and backwardly across the road in a zig-zag manner. The roller being of considerable length 45 and being perfectly straight, will act as a straight edge longitudinally of the road to smooth down the surface. The carriage or bridge is entirely open or unobstructed between the platforms or boards 15, and between the side rails or forms 14, in order that 50 the roller 7 may operate without interference on the surface of the concrete between said platforms or boards. 55 The frame of the carriage comprises longitudinal side beams 17 which are located outwardly beyond the side rails or forms 14, and the transverse trusses 18. Said trusses and beams are connected by braces 19. Uprights 20 are secured to the trusses 18 between the 60 ends thereof and are connected at their upper ends by a bar 21 which is sufficiently high to permit the workmen to walk under said bar 21. The uprights 20 and bar 21 provide an arch connecting the front and rear trusses 18 so as to brace and strengthen the frame of

the carriage without obstructing the space between the platforms or boards 15.

The roller being of the weight hereinbefore mentioned is especially useful on the concrete after it has passed through its initial settling action. When the concrete or aggregate is poured, such as when building a concrete road, it settles down of its own accord as the water gradually trickles out and the air escapes. It is after such natural exuding or oozing out of the water and air, and not before, that the present roller is used, in order to still further settle the concrete and bring out more of the remaining water and air. The concrete is brought to this condition in a natural way, and this stage is reached immediately after the free water has drained off. With the concrete in this condition, a second stage is produced with the application of the roller to the concrete, which compresses and forces down the aggregate. Thus, the stone and sand are forced into the pockets, which previously contained air and water, resulting in the forcing out of still more air and water. Furthermore, the compressive action of the roller will cause the particles of stone, gravel, sand and cement to be wedged together more closely, thereby producing a concrete structure of greater strength and density than produced by the use of a light floating roller. The present roller being of the weight hereinbefore indicated will, when passing over high spots in the concrete, press them down. The present roller cannot be used on freshly laid concrete because it will sink therein, being too heavy to be used as a floating roller, and a floating roller is not required, nor is it present.

The concrete after being poured, regardless of how smooth it may be surfaced immediately after pouring, will, after the water is drained therefrom, again have an uneven surface. This is due to the fact that more water exists in some spots than others. Consequently at one spot where there is an excess of water, a low place or depression will be left on the surface of the road, and at other spots which are drier there may be raised portions in the surface. It is for the crushing or pressing down of the concrete and especially high spots subsequent to preliminary finishing that the roller is intended, the roller when passing over the high spots crushing them down and pressing them flat. At the same time, the weight of the roller will spread the concrete at the high spots, so as to level off the surface, and to bring out more of the remaining water.

Ordinarily, when concrete is agitated as is done by excessive tamping, a grout composed of water, cement and sand is brought to the top, at times even as much as one inch in depth. This is contrary to the ideal condition, wherein the mixture should be just the

same as that delivered by the mixing machine, with a top finish added. Therefore, with the use of the present roller, the concrete after being poured is struck off and may be rolled with a light floating roller, and is then allowed to settle of its own accord until such time, as hereinbefore stated, when the present heavy roller is used to smooth down the top surface.

10 In order to prevent the roller from moving off the edges of the road, the side beams or members 17 of the carriage have spring stops 16 against which the roller contacts when moved to the rails 14.

15 Figs. 3 and 4 illustrate a modification, the handle bars 8 being removed and substituted by operating means which enable the roller to be operated with the workmen at the opposite sides of the road. Thus, short bars 8' are 20 loosely mounted between their ends on the trunnions or pivots 11, which may be removed to receive either the bars 8 or the bars 8'. Wires, ropes or other flexible elements 9' are secured to the opposite ends of the bars 8', and 25 there are two flexible elements at each end of the roller extending to the opposite sides of the road. These flexible elements may be grasped in the hands of the workmen for alternately pulling the roller to the opposite 30 sides of the road. Any one flexible element may also be pulled, or diagonally opposite flexible elements pulled, for angling the roller on the surface in order that it can be zig-zagged. In order to prevent the roller from 35 being accidentally pulled off the road, suitable stops 16' may be provided at suitable intervals along the rails or side forms 14 against which the roller moves when reaching the edges of the road.

40 Figs. 5 and 6 show the carriage or bridge of Fig. 1 with modifications or additions. The carriage shown in Figs. 5 and 6 may be used as shown in Fig. 1, and, as shown in Figs. 5 and 6, the carriage has means connected with the roller or finishing device 7 for moving it across the concrete. For this purpose, longitudinal shafts 24 are provided at the opposite sides of the carriage frame, being shown as being located above the beams 45 17, and said shafts are journaled in bearings 25 secured to the ends of the trusses 18. The shafts have cranks 26 or other means at their ends for conveniently rotating the shafts. The roller has the same operating elements 50 as shown in Figs. 3 and 4, and the roller is located between the platforms or boards 15, with the flexible elements 9' secured to the shafts 24 to be wound thereon. By rotating one shaft the corresponding flexible elements 55 9' are wound thereon to pull the roller across the concrete to the corresponding side or edge of the road, the opposite flexible elements being unwound from the opposite shaft, and said opposite shaft may then be rotated to 60 wind the corresponding flexible elements

thereon and move the roller reversely. Either one or two men may be used for alternately rotating the two shafts 24, and the roller may be moved across the road any number of times. Any one of the flexible elements may be pulled when it is desired to pull only one end of the roller, for angling the roller on the concrete surface should same be desired, and the roller will be straightened out longitudinally of the road when the flexible elements are again wound on either shaft.

Angle bars or members 16'' are secured to the beams 17 of the carriage frame and have lower horizontal portions at about the same levels as the treads or upper edges of the rails or forms 14, with said horizontal portions projecting toward said rails. These members 16'' serve as stops to limit the movements of the roller transversely, and the lower horizontal portions of said members serve as supports or platforms on which the roller can move to be supported from the carriage. Thus, the roller may be moved across either rail or form 14 onto the corresponding members 16'' to limit the movement of the roller, and to support the roller from said members, in which event the roller may be moved longitudinally of the road with the carriage. This enables the roller to be readily moved from one position to another along the road for the successive finishing operations, it being understood that the roller is moved longitudinally less than the length of the roller, so that the surfaces finished in succession by the roller will overlap.

Fig. 6 also shows the wheels 13 as being double-flanged so that their flanges overlap the inner and outer sides of the rails 14, and said wheels are disposed on transverse axles 22 for transverse adjustment so as to accommodate roads of different or varying widths, as will be apparent. The wheels 13 at one side are maintained in transverse adjustment by means of collars 23 on the respective axles secured to the axles by means of set screws or other suitable clamping elements, while the wheels at the opposite side are free to slide transversely should the rails 14 at the opposite sides be spaced apart different distances, such as when negotiating curves. The stops and supporting members 16'' need only be used at one side, preferably at that side at which the wheels 13 are maintained in transverse adjustment so that the members 16'' will be maintained in close relation with the corresponding rail or form 14. It is desirable, however, to have means for stopping the roller at the opposite side of the carriage also to prevent the roller from moving off the road to the ground.

Having thus described the invention, what is claimed as new is:—

1. A travelling carriage movable over a concrete road or similar structure having means substantially flush with the surface of

the road or structure for receiving and carrying a finishing device, normally unsupported from the carriage when said device is moved off the road or structure beyond one edge thereof.

- 5 2. A travelling carriage movable over a concrete road or similar structure, a finishing device movable transversely across the concrete and normally unsupported from said carriage, and means carried by the carriage beyond one edge of the road or structure substantially flush with the surface of said road or structure to receive the finishing device thereon when moved off the road or structure beyond said edge thereof, so as to support and carry said device from the carriage.
- 10 3. A travelling carriage movable over a concrete road or similar structure, a roller to roll transversely across the concrete and normally unsupported from said carriage and means carried by the carriage at the opposite edges of the road or structure to limit the movements of the roller and having portions substantially flush with the surface of the road or structure to receive and support the roller when moved off the road or structure.
- 15 4. The combination of a roller for preparing a concrete structure while in plastic condition, and a carriage movable over said structure and having means flexibly connected to the roller for operating the roller transversely of itself without supporting the roller from the carriage and having means for supporting said roller for movement longitudinally from one position to another.

In testimony whereof I hereunto affix my signature.

JOSEPH WILLIAM HELTZEL.
